UNITED STATES PATENT OFFICE.

GEORGE FREDERICK SHAVER, OF NEW YORK, N. Y., ASSIGNOR TO THE SHAVER CORPORATION, OF SAME PLACE.

MECHANICAL TELEPHONE.

SPECIFICATION forming part of Letters Patent No. 392,233, dated November 6, 1888.

Application filed March 31, 1888. Serial No. 269,140. (No model.)

To all whom it may concern:

Be it known that I, GEORGE FREDERICK SHAVER, a citizen of the United States, and a resident of New York, in the county and State 5 of New York, have invented certain new and useful Improvements in Mechanical Telephones, of which the following is a specification.

My invention relates to devices employed in transmitting speech, and has for its object the 10 provision of a mechanical telephone of greater vibratory power than has been heretofore attained, and of means for focusing the sound-waves thrown off from the diaphragm-reflector placed opposite the mouth-piece, and of other 15 particulars hereinafter described.

To attain the desired end, my invention consists in the construction and arrangement of parts, as and for the uses and purpose set forth.

In the accompanying drawings, which form 20 a part of this specification, Figure 1 represents a central vertical section of my telephone on the line x x , Fig. 2. Fig. 2 is a front elevation, and Fig. 3 a side view, of my device. Fig. 4 represents a view of the back of the instrument, and Fig. 5 is a detail view.

Like letters of reference, wherever they occur, indicate corresponding parts in all the figures.

Referring again to the drawings, A represents a (preferably) square frame, case, or box resting upon two parallel base string-pieces, A', extending a short distance beyond the sides of the box. The back of the box A², which serves as a sounding-board, and which 35 rests, as stated, upon the string-pieces A', is, by this construction, held away or raised from any surface to which my telephone-box A may be attached—as, for instance, a wall—the instrument being secured to the same, however, 40 by screws or nails inserted through the projecting ends of the string-pieces.

At the corners of my box A are placed four corner-posts, A⁴, which are provided with slots adapted to receive and securely hold the ends 45 of the thin side boards, A², of my telephone-box, as shown in Figs. 2, 3, and 5.

Four flat string-pieces, B', forming a rectangular frame, are placed upon the corner-posts A⁴ and side boards, A², and behind the 50 inner face of my sounding-board B, which forms the face of my box, for the purpose of strength-

ening my box A, and the various parts are held together by bolts or screws b passing through the sounding-board B and string-pieces B' into the corner-posts A⁴.

55

Preferably placed upon the sounding-board B are one or more exterior sounding-boards, I, separated by narrow strips i, the sounding-boards A³, B, and I being connected together by means of four sounding-posts, H, as is 60 clearly shown in the drawings.

A concentrating mouth-piece, C, constructed of vibratory material, may or may not be fitted to the sounding-board B for convenience in use.

A diaphragm, D E, constructed (preferably 65 in two parts) of compressed fibrous material—as, for example, “leatheroid” or “vulcanized fiber,” which I find peculiarly adapted for use in this connection—is fastened to the inner side of the sounding-board B by the following 70 means: The diaphragm-plate D is secured by the screws d to the board B, and is preferably depressed or concave at its center and adapted to be connected with a line-wire, F, as in the present instance, by being provided with a 75 central opening in order to receive a concave or dome-like vibratory diaphragm-reflector, E, of parabolic section, provided with a flanged edge placed between the diaphragm-plate D and sounding-board B. The sounding-board 80 B is under tension while in use, and vibrates simultaneously with the diaphragm D.

A button, G, constructed of non-metallic material, is placed under the diaphragm-reflector E, and the elongated shank of the same 85 serves to provide a means for attaching my line-wire F and my diaphragm-reflector E together. The button G and elongated shank is made of non-metallic material in order to do away with the resonance experienced in the 90 use of metals, and, being lighter, secures better articulation.

The bottom edges of the side boards, A², of my box A are ordinarily cut away in order to more readily allow the sound-vibrations egress. 95

The action of the instrument when used as a receiver is as follows: When the vibrations of the line-wire F reach the diaphragm-reflector E, it is thrown into vibration, and the sound-waves thrown off from its sides are 100 brought to a focus at the center of the opening in the sounding-board B and of the mouth-

piece C. The diaphragm-plate D is also thrown into vibration, and, being attached to the board B, the sounding-boards B, A³, and I (connected by the posts H) are simultaneously caused to 5 vibrate, the effect of the combined sounding-boards and diaphragm D E vibrating in unison being to greatly increase the power or loudness of the sounds emitted by the telephone.

Although I have shown the diaphragm D E 10 as constructed of two pieces, yet it is obvious that from one and the same integral material the diaphragm-plate and reflector may both be formed, and the line-wire F may be attached directly to the diaphragm-reflector E, and the 15 sounding-boards I may also be dispensed with, if desired.

As it is evident that many slight changes in 20 the construction and relative arrangement of parts might be resorted to without departing from the spirit and scope of my invention, I would have it understood that I do not restrict myself to the particular construction and arrangement of parts shown and described, but that I reserve the right to make such changes, 25 and that

What I claim as new, and desire to secure by Letters Patent, is—

1. In a mechanical telephone, the combination 30 of a diaphragm, an apertured sounding-board under tension extending entirely over and supporting said diaphragm, and a connecting line-wire, substantially as set forth.

2. In a mechanical telephone, a supporting 35 frame or case, in combination with an apertured sounding-board extending over the entire front of said case and supporting under tension a diaphragm connected with a line-wire, F, attached beneath or back of the said

sounding-board B, substantially as herein set forth.

3. In a mechanical telephone, a supporting frame or case, in combination with a diaphragm and a sounding-board under tension extending across the face of the said diaphragm and forming a support therefor, and provided with a 45 central opening and a concentrating mouth-piece, substantially as set forth.

4. In a mechanical telephone having a sounding-board extending across the face of the telephone and provided with a central aperture, 50 the said sounding-board being under tension while in use, the combination, with the sounding-board, of a line-wire, and a diaphragm secured to the inner or under side of said sounding-board and adapted to vibrate simultaneously with the same.

5. In a mechanical telephone, the combination 55 of a frame or case, a sounding-board extending over the front of the said case and having a central aperture, a diaphragm secured to the inner side of the same, and a converging reflector, as set forth.

6. In a mechanical telephone, the combination 60 of the string-pieces A', side boards, A², sounding-boards A³ B I, corner-posts A⁴, 65 mouth-piece C, reflector E, diaphragm D, the line-wire F, and sounding-posts H, substantially as herein set forth.

Signed at New York, in the county of New York and State of New York, this 30th day of 70 March, A. D. 1888.

GEORGE FREDERICK SHAVER.
